UNITED STATES PATENT OFFICE.

ALPHONSE BAYE, OF LONDON, ENGLAND, ASSIGNOR TO THE ROXBURY CARPET COMPANY, OF BOSTON, MASSACHUSETTS.

DESIGN FOR CARPETS.

Specification forming part of Design No. 9,903, dated April 17, 1877; application filed April 3, 1877.
[Term of Patent 3½ years.]

To all whom it may concern:

Be it known that I, ALPHONSE BAYE, of London, England, have invented a new and original Design for Carpets, of which the following is a specification:

The nature of my design is fully shown in the accompanying photographic illustration, numbered 1,338.

I claim—

The design for carpets, as shown in the accompanying photographic illustration.

In testimony whereof I have signed my name to this specification in the presence of two subscribing witnesses.

ALPHONSE BAYE.

Witnesses:

HENRY COOPER,
CHARLES JOSEPH COOPER.
